UNITED STATES PATENT OFFICE.

FRED E. TOOTHAKER, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

ART OF SHOEMAKING.

Application filed May 2, 1925. Serial No. 27,502.

To all whom it may concern:

Be it known that I, FRED E. TOOTHAKER, a citizen of the United States, residing at Swampscott, in the county of Essex and 5 Commonwealth of Massachusetts, have invented certain Improvements in the Art of Shoemaking, of which the following description, in connection with the accompanying drawings, is a specification, like reference characters on the drawings indicating like parts in the several figures.

This invention relates to the art of making shoes and particularly shoes in which the heel portion of the upper is turned inwardly over the heel-seat of the last, and the upper at the shank and forepart is turned outwardly, that is, to stitchdown shoes having the heel-seats lasted inwardly. In the manufacture of shoes of this type, in 10 accordance with practise heretofore common, a molded counter having the usual inwardly turned sole attaching flange has been employed which is placed between the upper and lining and the upper is placed on a last 15 having an innersole thereon of the size and shape of the bottom of the last. The lining at the shank and forepart as well as at the heel is lasted in over the innersole, and a comparatively thin middle sole having its 20 margin extending beyond the bottom of the last is placed upon the shoe and temporarily secured to the last. The margin of the upper at the shank and sides of the shoe is then lasted and permanently secured in the 25 angle between the margin of the sole and the side of the last. Thereafter the upper is lasted inwardly over the heel-seat and secured thereto and finally an outersole is applied and stitched with the usual welt 30 strip to the projecting margin of the middle sole and the outturned flange of the upper. In order properly to secure the wings of the 35 molded counter in position, it has been found necessary to perform a separate tacking 40 operation between the operations of lasting the upper as described and the lasting of the heel-seat, the wings of the counter in this operation being held in by securing the forward part of the inturned flange of 45 the counter to the innersole. An object of 50 this invention is to render this separate counter-wing-securing operation unnecessary.

To this end, the invention provides a 55 novel counter having its sole attaching flange

inturned about the heel-seat portion of the counter but having the portions of its flange adjacent to the wings of the counter outturned. The outturned portions of the counter flange are shaped and arranged to 60 be readily positioned and secured to a middle sole or outersole in the operation of lasting and securing the margin of the upper at the shank and sides of the shoe by the lasting 65 fastenings. In another aspect the invention 70 comprises an improved method, especially adapted for use in making stitchdown shoes of the type referred to, which is characterized by providing such a counter and by 75 lasting and securing the upper including the outturned portions of the counter to the margin of the middle sole, after which the 80 heel-seat lasting and securing and the other subsequent operations may be performed as heretofore. In still another aspect, the 85 invention provides a novel stitchdown shoe having a counter provided with outturned flange portions adjacent to the wings of the counter, the heel-seat portions of the counter and upper having inturned margins secured 90 to the innersole while the upper forwardly of the heel-seat has outturned margins which, together with the outturned portions 95 of the counter wings, are attached to the middle sole by the upper lasting fastenings.

In the drawing:

Fig. 1 is a view of a counter made in accordance with the present invention and showing its relation to the inner and middle soles, the upper and lining being omitted;

Fig. 2 is a perspective view, partly broken away and partly in section, showing a shoe including the novel counter in process of construction, the last being omitted;

Fig. 3 is a transverse sectional view of 95 the shoe and last, the section being taken through the outturned portion of the counter;

Fig. 4 is a perspective view of the shoe 100 after the sides and heel-seat have been lasted; and

Fig. 5 is a side elevation, partly in section, of the rear end of a shoe embodying this invention.

In the manufacture of a shoe in accordance with the present invention, the margin of the counter which is to form the sole attaching flange is slit at a distance from the front end of the counter, the margin at the rear of the slit being turned and molded 105

inwardly and the upper forward of the slit being turned and molded outwardly, as shown in Fig. 1, in which 2 indicates the vertical body portion of the counter, 4 the inturned portions of the sole attaching flange, and 6 the outturned portions of the said flange. A last 8 is provided with an innersole 10 of the size and shape of the last and a counter formed as described is placed 10 between the lining 12 and outer layer 14 of the upper. The upper and counter are then placed on the last and innersole, and the lining lasted in over the innersole about the shank and forepart, the lining being secured 15 preferably by cement.

A middle sole 16 is next temporarily secured to the last, this sole being a relatively thin extension sole, that is, having a margin extending beyond the side of the last about 20 the whole periphery of the last bottom. The upper is lasted into the angle between the side of the last and the margin of the sole 16 about the forepart and shank by any suitable means and secured in said angle. As 25 shown, a stitchdown staple lasting machine has been employed to last the upper and secure it in the angle by means of staples 18 driven through the upper and middle sole 16 and clenched on the outer face of the middle sole. The margin of the upper is slit at each side at points corresponding to the slit in the counter between the inturned and outturned portions. Then, at the shank on each side at points adjacent to the heel-seat, 35 the upper and the outturned portion 6 of the counter are secured by one of the staples 18 to the middle sole. This counter construction enables the wings of the counter to be crowded in with the upper and the upper 40 and wings of the counter to be secured in proper relation to the middle sole as a part of the lasting operation and without special attention on the part of the operator, thus dispensing with the separate operation of 45 securing the wings of the counter in position.

After the shank and forepart are thus lasted and secured, the rear or heel-seat portion of the middle sole is turned back as 50 shown in Fig. 4, and the heel-seat of the shoe is lasted, the lining, inturned counter flange and upper being secured to the innersole 4 by tacks 20. The remaining operations in the manufacture of the shoe may be those 55 usually employed. The rear end of the middle sole 16 is laid down and an outersole applied and secured with the usual welt 22 to the upper and middle sole 16. It may be 60 desirable under some conditions to introduce between the rear end of the middle sole and the heel-seat an additional thin layer of material, this layer 24, as shown in Fig. 5, being equivalent in thickness to that of the

upper and the outturned portion 6 of the counter. It is thus possible to secure a better appearance of the shoe adjacent to the 65 end of the welt, the end of the welt being skived and allowed to overlap slightly the joint between the filler piece and the counter and upper.

Having thus described my invention, what 70 I claim as new and desire to secure by Letters Patent of the United States is:

1. A counter for shoes having the sole attaching flange at the wings of the counter turned outwardly and the remainder of the 75 flange turned inwardly.

2. A stitchdown shoe having an innersole, an upper lining having inwardly turned margins secured in lasted position to the innersole, a counter and an upper having in-turned marginal portions secured in lasted position to the innersole, and a middle sole, the upper and the portions of the counter adjacent to the wings of the counter having outturned marginal portions attached to the 85 middle sole.

3. A molded counter for shoes having the sole attaching flange adjacent to the wings of the counter molded outwardly and the remainder of the flange molded inwardly. 90

4. The method of making stitchdown shoes which consists in providing a counter having the major portion of its sole attaching flange inturned and portions adjacent to the counter wings outturned, placing the 95 counter between the outer layer and lining of the shoe upper, positioning the upper on a last having an innersole thereon, lasting the lining inwardly and securing it to the innersole, applying a middle sole, and lasting 100 and securing the upper and outturned portions of the counter to the margin of the middle sole.

5. The method of making stitchdown shoes which consists in providing a counter 105 having the major portion of its sole attaching flange turned inwardly and portions adjacent to the counter wings turned outwardly, placing the counter between the outer 110 layer and lining of the shoe upper, positioning the upper on a last having an innersole thereon, lasting the lining inwardly and securing it to the innersole, applying a middle sole, lasting and securing the upper and the wings of the counter in out-turned relation to the margin of the middle sole, lasting the heel-seat portion of the upper over upon the inturned margin of the counter, securing the upper and counter flange to the heel-seat of the innersole, and 115 completing the shoe in the usual manner.

In testimony whereof I have signed my name to this specification.

FRED E. TOOTHAKER.
